UNITED STATES PATENT OFFICE.

PAUL SABONADIER AND ETIENNE D'EAUBONNE, OF PARIS, FRANCE.

MANUFACTURE OF CARPETS AND SIMILAR FABRICS.

1,102,170.

Specification of Letters Patent. Patented June 30, 1914.

Application filed July 31, 1912. Serial No. 712,576.

To all whom it may concern:

Be it known that we, PAUL SABONADIER and ETIENNE D'EAUBONNE, citizens of the French Republic, residing at Paris, in France, have invented certain new and useful Improvements in the Manufacture of Carpets and Similar Fabrics, of which the following is a specification.

This invention relates to the preparation of pile warp or weft for the manufacture of carpets and similar fabrics, and it comprehends, briefly, certain hereinafter-described improvements in the process set forth in our prior Patent, No. 1,024,421, granted April 23, 1912.

The patented process consists, primarily, in the production of a warp or weft composed of a continuous band of "Cingalette" muslin, or the like, which is folded longitudinally and has secured between its sides a series of variously-colored pile threads, the latter being arranged longitudinally, one after another, in the order in which the corresponding colors appear in the pattern. Such process, however, when put into actual practice, has proved objectionable in some respects, notably in that the "Cingalette" band, which constitutes the sole means for connecting the threads together, is comparatively expensive; must be cut, folded and wound; must be woven with the warp into the pile; can be removed, after weaving, only with the greatest difficulty, and with great danger of injury to the fabric; and is entirely useless, and thus wasted, on being removed. On the other hand, with the present process, all of the afore-mentioned defects are overcome, or avoided, by forming the warp or weft merely by gluing together the adjoining ends of the pile threads, the adhesive being removable, after completion of the weaving, by simply dipping the woven fabric into a bath of water or other suitable liquid.

In carrying out the improved process, there may be utilized, for example, the apparatus represented in the accompanying drawings, whereof:

Figures 1, 2 and 3 are part-sectional side elevations of the mechanism for applying the adhesive, showing the various positions assumed thereby; and Fig. 4 is a part-sectional side elevation showing a light modification of the invention and, also, certain parts omitted from Figs. 1, 2 and 3.

As the spools, from which the short lengths or sections are taken, have the same arrangement and mounting as in our above-identified patent, and since the transfer of the selected spools into the apparatus and the application of the ends of the threads upon the conveyer are likewise effected in a substantially similar manner to that described therein, reference may be had to said patent for a complete exposé of such operations, and extended explanation and illustration in the present case are deemed unnecessary and, hence, are omitted. It is considered sufficient for present purposes, therefore, to state that, as in the earlier process, the threads that go to make up the warp or weft are wound on long spools, the number of which is equal to the number of successive picks comprised in the pattern, and that each of such spools is itself constituted by a series of individual spools arranged side by side upon a common spindle, the threads of these individual spools being of the same colors as the parts of the pattern to which they respectively correspond. Also, the threads are of sufficient length to enable the number of short lengths or sections requisite for the formation of the complete carpet to be taken therefrom. The long spools are brought in turn and in the proper order into operative position in the apparatus by means of suitable mechanism, and, on reaching such position, the ends of the threads that are wound on the component members of the long spool are deposited upon the above-mentioned conveyer and drawn through the apparatus to be acted on by the glue-applying mechanism, as subsequently described.

In the construction illustrated in Figs. 1, 2 and 3, a portion of the conveyer is represented diagrammatically in dotted lines, and, as shown, comprises a series of pivotally-connected members *g* in the form of cross-bars, each of which is so grooved as to constitute, in effect, a separate table. The number of such grooves is equal to that of the continuous warps or wefts to be produced, and the length of the conveyer itself, (which latter is of the endless type), is such that by the time that the warps or wefts have been removed therefrom the glue or other adhesive binding the ends of the short threads together will have completely solidified. The conveyer is given a step-by-step movement by means of driving

mechanism, (not shown), of any desired character. After the ends of the threads have been deposited in the conveyer grooves, the feed movement of the conveyer takes place, and the threads are brought beneath the glue-applying mechanism. An embodiment of this mechanism is illustrated in Figs. 1, 2 and 3, and it will be seen therefrom that said mechanism consists of a closed tank or container i , and a lever system for moving the same from one position to the other. The tank has a hopper-shaped front portion which is provided with a series of discharge tubes i^1 corresponding in number to the number of grooves in the conveyer members g , or, in other words, the number of threads undergoing treatment, and the passage of the agglutinant through these tubes is regulated by means of a series of rods i^2 which project thereinto, the tubes and rods thus coöperating to form needle valves, as will be understood. The said valve rods proper are attached at their upper ends to a cross-bar i^3 , controlled by a pair of retractile coil springs i^4 , the springs being arranged at the ends of the hopper portion of the tank and exerting their tension upon bar i^3 in such a way as to normally depress the valve rods and thus prevent discharge of the agglutinant from the outlet ends of the tubes i^1 . The latter are further provided with inlets i^5 , but said inlets, like the outlets, are normally closed owing to the depression of the valve rods. To maintain the agglutinant in a heated state, the tank may be equipped with a suitable heating coil i^6 . The tank is arranged for movement toward and from the conveyer, through the agency of the afore-mentioned lever system, and at the beginning of the former movement, the valves are opened so as to permit a certain amount of agglutinant to pass through the inlets i^5 into the discharge tubes i^1 and to be subsequently deposited upon the rear ends of the previously formed pile-threads when the rods i^2 are depressed. As represented in Figs. 1 to 3, the tank is provided upon its opposite sides with pairs of rollers i^7 and i^8 , which run upon pins, studs or the like affixed to the tank walls. The rear studs have also pivotally connected to them the front ends of a pair of links or bars i^{24} , which are reciprocated by means of suitable mechanism, (not shown), and it is these bars, therefore, which serve to produce the working or forward and backward movement of the tank, the latter sinking during its forward movement, and rising when moved backward. This effect is obtained through the coöperation of the pairs of rollers i^7 and i^8 with fixed or stationary inclines or cams i^9 and i^{10} mounted in the frame of the apparatus, the rollers traveling down the inclines when the tank is advanced, and upward when it is retracted.

To open the valves, there is provided a pair of two-armed levers i^{11} pivoted on pins or studs i^{12} at opposite sides of the tank and having their front arms engaged with the bar i^3 , to raise the same against the tension of the springs i^4 , when said levers are rocked clockwise. The movement just specified is produced by the action of a pair of levers i^{13} that are disposed directly above the rear arms of the levers i^{11} and are furnished with terminal rollers that engage and depress said arms, as will be understood from Fig. 1, such action being accomplished by the downward movement of a vertical rod i^{16} connected at its upper end to an arm i^{15} fastened to the rock shaft i^{14} which carries the said levers i^{13} . Means is provided, also, for retaining or locking the valves in open position during the forward movement of the tank. This locking is here shown as effected by means of a pair of spring-actuated pawls i^{20} which are pivoted upon opposite sides of said tank and are drawn by the tension of their springs into engagement with a pair of studs i^{21} provided upon the adjacent levers i^{11} , the arrangement being such that the engagement occurs after the clockwise rocking of said levers has been accomplished. At the end of the forward movement of the tank, the locking pawls are automatically released from engagement with the studs, and the levers then return to initial position, the disengagement being effected by a pair of arms i^{22} that are secured to shaft i^{14} and are designed to strike against a pair of studs i^{23} attached to said pawls. The levers i^{11} have finally associated therewith, a pair of spring-controlled auxiliary levers i^{22} which are pivoted at i^{23} to the bars i^{24} , and these levers i^{22} are so arranged as to be acted upon at their upper or rear ends by the corresponding ends of the said levers i^{11} , and as to engage at their front ends the tops of the cams or inclines i^9 , as shown in Figs. 2 and 3, in order to maintain the tank elevated and, also, in proper position with relation to a suitable device, (not shown), for cleaning the lower ends of the tubes i^1 . As previously explained, the opening of the valves for the purpose of permitting the entry of the agglutinant into the tubes i^1 takes place at the commencement of the forward movement of the tank. At the termination of this movement, the agglutinant is forced from said tubes, by the depression of the rods i^2 , upon the rear ends of the previously-formed pile-threads, the levers i^{11} being released at that time to effect such depression, by the action of the arms i^{22} which disengage the locking pawls i^{20} from the studs i^{21} , whereupon the springs i^4 are free to act. The tank is then retracted by the bars i^{24} , and at the same time the spool from which the last set of sections was taken is returned to the spool-carrier, a second

spool brought into the apparatus, and the ends of the threads wound upon its component or individual spools successively brought into alignment with the aforesaid last set of sections, straightened out, attached thereto, and finally severed. The mechanisms or devices for effecting these operations form no part of the present invention and may be either of the type shown in our prior patent, or of any other desired character; hence, they are indicated merely diagrammatically in Fig. 4, and will be given no extended description. It is sufficient to state, therefore, that the ends of the 10 fresh threads are first acted on by a rake *o*, which straightens them out and forces them into proper position against the coated rear ends of the last set of sections or threads, that set, as will be understood, having been 15 previously attached to the pile-threads already formed. Next, the said straightened ends of the fresh threads are acted upon by a compression mechanism *k*, which presses them against the coated ends of the last set 20 of sections or threads, thereby effecting the connection of the two sets of threads together. At about the same time, the long spool from which the fresh threads have been taken is moved a slight distance backward, in order to unwind the length sufficient for the formation of the new sections. Next, a second compression mechanism *m* is 25 brought into operation, and the first compression mechanism *k* simultaneously detached from the threads and moved backward, this second compression mechanism serving to press the connected ends of the 30 threads against the conveyer and thus attach the same thereto. The unwound portions of the fresh threads are then severed by the action of a knife *n*, after which the 35 second compression mechanism *m* rises, the conveyer advances, and the tank is moved forward, the agglutinant being deposited upon the free ends of the severed threads or 40 sections at the termination of such forward movement, the above cycle of operations being repeated until the formation of the continuous pile threads is completed. As the 45 ends of these continuous threads reach the end of the conveyer, they are removed therefrom, led between a pair of feed rollers *s* and *s'*, and wound upon a reel *h*, the latter having associated with it a variable-speed 50 take-up device, (not shown).

While the conveyer, which carries the threads through the apparatus, may advantageously be of the endless chain type, such conveyer, by reason of the fact that it consists 55 entirely of the pivotally-connected, grooved cross-bars, can be constructed only at a great expense. Accordingly, to cheapen the cost of the apparatus, a series of bands of muslin or other suitable material may be 60 substituted for the conveyer previously re-

ferred to, and a series of three cross-bars only used in connection with said bands. The short lengths or sections of thread are caused to adhere slightly to the bands during the formation of the continuous threads 65 and to travel therewith, and the said continuous threads can be readily removed from the bands prior to weaving, so that the latter may be repeatedly used. In Fig. 4, wherein this arrangement is illustrated, *r*¹ indicates 70 the roller on which the bands *r* are wound side by side, *r*² and *r*³ guide rollers for said bands, and *g*⁶, *g*¹⁰, and *g*¹⁰⁰ the three cross-bars over which the bands pass during 75 the gluing operation. These bars are 80 fixedly mounted in the frame *c*, and they are arranged for coöperation, respectively, with the knife or cutting mechanism *n*, and the second and first compression mechanisms *m* and *k*, the bar *g*¹⁰⁰ coöoperating, also, with 85 the rake *o*, which latter rests thereupon at the end of its forward stroke. The operation is otherwise similar to that previously described. The bands *r* may also be used 90 with the endless chain conveyer, if desired, as will be understood.

We claim:—

1. The process of forming pile warp or weft for use in the manufacture of fabrics, which consists in arranging separate threads 95 of various colors that are to constitute the pattern of the fabric longitudinally, one after another, in the order in which the corresponding colors appear in such pattern, and gluing the adjoining ends of said 100 threads together to obtain a single, continuous thread.

2. The process of forming pile warp or weft for use in the manufacture of fabrics, which consists in arranging the variously-colored threads that are to constitute the 105 pattern of the fabric longitudinally, one after another, upon a band in the order in which the corresponding colors appear in such pattern, and gluing the adjoining ends 110 of said threads together upon said band to obtain a single, continuous thread.

3. The process of forming pile warp or weft for use in the manufacture of fabrics, which consists in arranging the variously-colored threads that are to constitute the 115 pattern of the fabric longitudinally, one after another, upon a band in the order in which the corresponding colors appear in such pattern, gluing the adjoining ends of 120 said threads together upon said band to obtain a single, continuous thread, and removing the band from such thread prior to weaving.

4. A warp or weft for use in the manufacture of fabrics comprising a continuous thread consisting of a series of separate, short lengths of threads of various colors arranged longitudinally, one after another 125 in the order in which the corresponding 130

colors appear in the pattern of the fabric, and having their adjoining ends glued together.

5. The combination, with a flat band of textile material, of a warp or weft comprising a continuous thread consisting of a series of separate, short lengths of thread of various colors arranged longitudinally, one after another in the order in which the corresponding colors appear in the pattern of the

fabric, said threads having their adjoining ends glued together and to said band.

In testimony whereof we have signed our names to this specification in the presence of two subscribing witnesses.
